P. ANDRUS, OF ROCHESTER, NEW YORK

ABRADING BRUSH

Application filed August 13, 1930. Serial No. 474,908.

The present invention relates to abrading brushes, and an object thereof is to provide a construction which will employ coiled wire as its bristles to obtain the maximum abrading action while giving durability to the brush. Still another object of the invention is to associate bristles of coiled wires in tufts or groups in such a manner that the bristles of each group or tuft acts as supports for each other. A further object of the invention is to provide an abrading brush having coiled bristles so mounted as to confine the abrading action substantially to the free ends of the coils. A still further object of the invention is to so support coiled bristles that the crystallization of the bristles is delayed to give longer life to the brush. Another and further object of the invention is to provide a novel method of forming a tuft of coiled bristles. Still another and further object is to provide novel supporting means for the brush tufts.

In these and other ends, the invention consists of certain parts and combinations of parts all of which will be hereinafter described, the novel features being pointed out in the appended claims.

In the drawings:

Fig. 1 is a side view of a hand abrading brush embodying the present invention;

Fig. 2 is a bottom view;

Fig. 3 is a perspective view of the anchoring plate or member used in the embodiment shown in Figs. 1 and 2;

Fig. 4 is a vertical section through one of the tuft elements;

Fig. 5 is a bottom view of one of the tuft elements;

Fig. 6 is an enlarged fragmentary sectional view of one of the tuft elements;

Fig. 7 is an axial section through a rotary abrading brush embodying the present invention, the tuft element being also modified;

Fig. 8 is a side view with parts broken away of the brush shown in Fig. 7;

Figs. 9 and 10 are fragmentary detail views of the brush shown in Figs. 7 and 8;

Figs. 11, 12, 13 and 14 are fragmentary views of different modifications of the coiled bristles;

Figs. 15 and 16 are views showing steps in the method of making the tuft element;

Fig. 17 is a perspective view of the bristle holding cap before it is applied to a tuft of bristles.

Fig. 18 is a side view of the tools by which the bristles are assembled in the cap before the cap is fitted to the bristles;

Fig. 19 shows the tools in vertical section with the cap fitted to the tuft of bristles;

Fig. 20 shows the manner in which the bristles are distorted at their upper ends to hold them in the caps;

Fig. 21 is a bottom view of another embodiment of the invention;

Fig. 22 is a vertical section of the embodiment of the invention shown in Fig. 21; and

Fig. 23 is a view of another embodiment of the tufts in which the bristles are soldered together.

In the illustrated embodiments of the invention, the abrading brush has bristles in the form of closely wound wire coils arranged so that each coil has lateral support substantially throughout its length by other coils. Preferably the coils are arranged in groups or tufts in order to give a certain amount of lateral flexibility while providing spaces between the groups or tufts in which the loose material may pass. The lengths of the coils

with reference to the outside diameters are preferably such that while flexing slightly during the abrading action the coils will support each other. It is preferred to employ a highly tempered steel wire such for instance as a piano wire wound for example to an outside diameter of thirty-five thousandths of an inch to one eighth of an inch and having a coil length for example of one-fourth

of an inch to one and one-fourth inches, the smaller the diameter, the shorter the length of the coil so that when arranged closely assembled, their group flexibility will not be too great or can be reduced to a minimum.

The free ends of the coils preferably lie in a single plane transversely of the coils and may be formed in various ways to obtain different cutting actions. In Fig. 11, the coil 1 has an end 2 which is ground to produce a knife edge, in Fig. 12 the end 2 is separated

from the coil 1, in Fig. 13 the end 2 is bent

at an angle to the coil 1, and in Fig. 14 the end 2 is bent at an angle to the coil 1 and has

an edge 3 which is ground to produce a knife edge.

The anchoring plate 4 is shown in Fig. 3 and

is provided with a central opening 5 through

which the brush 1 is passed. The plate 4 is

slightly from the coil and is pointed; whereas in Fig. 13, the end 2^b is arranged close to the coil and is pointed. Each gives a different cutting or abrading action which is adapted 5 for a different type of material or work.

Where extremely heavy work is required, the bristle shown in Fig. 14 may be employed comprising two closely wound coils 1^a and 1^b of different diameters both in the coils and the 10 wire and arranged one within the other but wound in different directions thus providing two cutting points 2^c and 2^d.

The group or tuft arrangement of the coils may be obtained by providing for each group 15 a separate group holding device. Three examples of the holding device are shown, one in the embodiment illustrated in Figs. 1 to 6 and another in the construction shown in Figs. 7 to 22 and the third in Fig. 23.

20 In the example illustrated in Figs. 1 to 6, the group coils 1 are held at one end by a cap which has its side or flange pressed inwardly and outwardly at 3 on an inward curve, the inner portion of the curve being spaced from the top of the cap and the outer portion 5 of the flange being substantially perpendicular to the top of the cap. The top of the cap is forced by pressure against the ends of the coils and causes said ends to be placed under compression with the cap, causing 25 the ends of the outer coils to spread outwardly beyond the sides of the group. The central portion 6 of the top of the cap is not subjected to as much pressure as the marginal or edge portion 4 with the result that the outer coils are clamped or gripped between the portion 4 and the curved portion 3 of the coils. While the flange of the cap is pressed tightly against the sides of the group of coils, 30 it is not so much this pressure of the flange that secures the coils as it is the expansion or spreading of the cap adjacent its base and the compression and spreading of the coils into the expanded or spread portion of the cap. This spreading may be assisted by eliminating one or more coils at the center of the group as shown at 7, Figs. 4 and 5 and providing a central opening in the cap with a surrounding inwardly extending flange 8 35 which will project into the space provided by elimination of the central coil, this flange assisting in the spreading of the adjacent ends of the coils as at 9 and more effectively holding the group of coils. The elimination of the central coil also gives greater flexibility to the group or tuft of coils and provides a space where fine particles may collect. It also may serve as a feeding space for a lubricant fed through the opening in the holding cap.

40 In the second example, the holding cap is the same except that it does not have the central opening in its top, and the central coil is not removed from the group. This construc-

tion is preferably used when greater rigidity is desired in the group or tuft of coils.

The third example of the tuft or group of bristles is shown in Fig. 23. In this construction the parallel arrangement of the 70 bristles is obtainable in a more simple manner and while the cap construction is preferred in many instances, this modified form has advantages. In this modified form, the bristles are held in close parallel relation and are dipped in solder which flows between the coils and also into the coils forming practically a homogeneous holding body at the upper ends of the coils. This construction does not require the compression of the coils. 75

80 A novel means which may be employed for making and attaching a cap to the group of tuft or coils (see Figs. 15 to 20 inclusive) comprises, in this instance, a holding tool in the form of an open ended sleeve or tube 10 of 85 hard steel arranged in a carrier 11 and having its upper end flared at 12. A plunger or rod 13 is adjustable longitudinally in the carrier 11 and the sleeve 10 by means of a screw 14 engaging the lower end of the plunger. The upper end of the plunger forms the bottom of a chamber whose side walls are formed by the inner face of the sleeve 10. This chamber serves to receive and confine the group of coils while the cap is being applied thereto. With 90 the end in view of fitting the group of coils in this chamber, the number of coils (previously determined) to be assembled in the group are collected and an open split band 15 is passed about them and clamped by pinchers or pliers 16 as shown in Fig. 16 to close the band. The coils project from one side of this band so that their projecting portions may be introduced into the chamber of the holding tool. During 95 their introduction the split confining sleeve 10 is slipped off the group, the coils of which are caused to engage the bottom of the chamber. At this time the upper ends of the coils in the group project slightly above the top of the chamber and the upper end of the sleeve 10. While in this position the group of coils 100 has a cap fitted thereover. The form of the cap at this time is shown in Fig. 17. Its flange throughout the height thereof is perpendicular to the top of the cap or is of uniform diameter, the interior diameter being only slightly greater than the external diameter of the group or tuft of coils so that the cap fits snugly about the group of coils. The upper ends of the coils abut the top of the cap 105 while the free edge of the flange of the cap lies over the flared portion 12 of the sleeve 10. Arranged to operate above the cap is a plunger die 17 (see Figs. 18 and 19) which has a slight depression 18 in the underside, the diameter of this depression being slightly less than the diameter of the cap shown in Fig. 17. When the two tools are forced together, the upper side portion of the cap expands as 110 shown in Fig. 20, the top of the cap is forced 115 into the depression 18 and the cap is held in place by the plunger die 17. The cap is then 120 forced over the top of the coils and the plunger die 17 is withdrawn. The cap is then forced 125 over the top of the coils and the plunger die 17 is withdrawn. The cap is then forced 130

against the upper portions of the coils, and the portion 5 is compressed against the sides of the group of coils with the results that the upper ends of the coils are compressed and deflected or spread outwardly, those portions adjacent the bulged portion of the cap bending into said bulged portion or in other words being clamped or gripped between the portion 4 and the portion 3 of the cap. At the same time, the group of coils are pressed together sidewise by the portion 5 which enters the main bore of the sleeve 10.

The sleeve holds the group of coils against distortion beyond the cap so that the group has a substantially cylindrical form beyond the cap held in this position by the portion 5 of the cap and each coil lies in abutment with the proximate coils substantially throughout its length and is thereby supported laterally.

Various means may be employed for supporting the group or tuft elements shown herein. However in each of the supporting means it is preferred to employ an anchoring device which will permit the group element to turn or rotate therein and will act as a support for the coils or bristles beyond the cap, and will tend to cause the cap to tighten on the bristles.

In the embodiment of the supporting means shown in Figs. 1 to 3 inclusive, when the invention is embodied in a hand brush, 18^a indicates a brush head having a handle 19. The head has an anchoring member secured thereto and preferably comprising a plate portion 20 having two converging flanges 21 projecting from the rear face thereof and secured to the head 18 preferably by producing two converging abutments 22 on the head for engagement by the converging flanges 21. The plate portion 20 lies in spaced relation to a surface 23 on the head, and is provided with openings. About these openings are rearwardly projecting and flaring annular flanges 24 which act as seats for engaging the flanges of the caps of the group or tuft elements while the bottoms of the caps rest against the abutment surface 23, with the result that the group or tuft elements may turn in the anchoring member, and the flared seats of the latter tend to force the flanges of the caps in tight engagement with the coils. Beyond each seat, each opening is surrounded by a flared wall 25 which will engage a group of bristles beyond the holding cap thereof. This flared portion

acts to prevent the sharp bending of the coils by the free edge of the cap and thus adds life to the coils by making them not so liable to crystallization from bending. With this form, worn out group elements may be replaced by shifting the anchoring member on the guides of the brush head to remove the anchoring member with the group elements thereon.

In the supporting means shown in Figs. 7 to 10 inclusive, the anchoring member is in

the form of a strap or split band 26 on a drum or wheel formed, in this instance, by two disks 27 having abutting depressed central portions receiving bearing members 28 and held against a collar or shoulder 29 on a shaft 30 by a nut 31. By substituting members 28 having different sized bearing openings, shafts of different diameters may be employed in connection with the brush. The supporting disks 27 are also provided between them with abutments 32 in the form of inwardly pressed annular ribs against which the caps of the group elements rest or abut and beyond these abutment ribs 32 or adjacent the margin of the wheel annular inwardly presented shoulders 33 are provided and on the inner sides of these shoulders the band or strap engages. One end 34 of the strap is turned outwardly to provide a lip which is received in notches 35 in the two annular abutments 33 to hold the strap against turning on the supporting means. The strap or anchoring member has inwardly turned flaring flanges 24 acting as seats for the caps of the groups or tufts of bristles and also has flared portions 25 serving to support the bristles beyond the caps. The coiled bristles are of special advantage when used with a brush of this type for when the brush is rotated in a direction to carry the peripheral portion downwardly in front of the operative the bristles have a tendency to spring or snap downwardly after being engaged and placed under lateral tension by a work piece, thus preventing centrifugal force carrying the bristles back to the operative and possibly injuring his eyes or face.

In the embodiment shown in Figs. 21 and 22, the holder embodies a stem 36 having an annular shoulder 37 against which abuts a cup shaped or flanged abutment member or holder 38. In this holder is received an anchoring member in the form of a disk 39 formed with flaring seats 24 for the caps of the groups or tuft elements which abut the holder 38, project through the opening of the anchoring member 39 and are supported in their bristles beyond the caps by the flaring portions 25 about the openings. The anchoring member 39 may be held to the holder 38 by upsetting the end of the shaft 36 over the outer face of the anchoring member 39 after passing the shaft through the anchoring member.

From the foregoing it will be seen that a novel and effective abrading brush or tool having coiled bristles has been provided.

What I claim as my invention and desire to secure by Letters Patent is:

1. The combination with a tuft of coiled bristles, of a holding device surrounding the tuft and in the form of a cap forming a band exteriorly compressed around the tuft of bristles to clamp the same, said cap having a marginal expanded portion adjacent the

top wall of the cap into which the ends of the coils are laterally deflected to spread the same, said top wall holding the ends of the coils under compression.

- 5 2. The combination with a tuft of coiled bristles, of a holding device surrounding the tuft and in the form of a cap forming a band exteriorly compressed around the tuft of bristles to clamp the same, said cap having 10 a marginal expanded portion adjacent the top wall of the cap into which the ends of the coils are laterally deflected to spread the same, said top wall holding the ends of the coils under compression, and the side walls 15 of the cap having an inwardly tapering curve below said expanded portion.
3. The combination with a tuft of coiled wires, of a holding device for the coils in the form of a cap including a top wall and 20 a side wall and made of sheet metal and forming a band exteriorly compressed around the bristles to clamp the same, said cap having its top wall holding the adjacent end portions of the coils under compression and 25 the side wall of the cap holding the sides of the tuft under greatest pressure away from the extreme top ends.

4. The combination with a tuft of coiled bristles, of means for securing said bristles 30 together at one end, comprising a band exteriorly compressed intermediate of its edges to clamp the bristles, said band being expanded between its compressed portion and the inner ends of the bristles, the inner ends 35 being laterally deflected and spread within the expanded portion of the band.

5. The combination with a tuft of coiled bristles, of means for securing said bristles together at one end, comprising a band exteriorly compressed intermediate of its edges to clamp the bristles, said band being expanded between its compressed portion and the inner ends of the bristles, the inner ends 45 being laterally deflected and spread within the expanded portion of the band, and the inner end of the band being extended inwardly over the ends of the bristles.

6. An abrading brush having bristles formed of two coils one within the other.

- 50 7. The combination with a tuft of coiled bristles and means for securing said bristles in close arrangement at one end, of an anchoring member having openings through which the tufts of bristles are passed, the 55 walls of the openings engaging the bristles beyond said securing means flaring outwardly.

8. An abrading brush comprising a tuft of coiled bristles, means for securing said 60 bristles together at one end, and a flared surface surrounding said tuft beyond said secured portions to prevent sharp bending of the coils adjacent their secured portions.

9. The combination with a tuft of bristles, 65 of annular means having a tapering portion

securing said bristles together at one end, and an anchoring member having a flared annular seat in which said tapered means is received and in which said tuft has rotative movement.

70 10. The combination with a tuft of bristles, and annular means securing said bristles together at one end, of an anchoring member having a circular opening in which said tuft is mounted to turn about an axis extending 75 longitudinally of the tuft so that an equal wearing action on the tuft is obtained.

11. The combination with a support having an abutment, of an anchoring member carried by the support and provided with an opening, the outer portion of the wall of which flares, a flared annular seat about the opening on the side next to the abutment, and a tuft of bristles abutting the abutment, extending through the opening, and having 80 an annular bristle holding means seated in the seat and rotatable therein to permit the tuft of bristles to turn, the bristles beyond the holding means being normally spaced from but engageable with the outer flared 85 portion of the wall of the opening.

12. An abrading brush comprising a ring shaped bristle support having openings, a tuft of bristles extending through each of 90 said openings, and two disk like members supporting the ring shaped bristle support and each having a surface engaging the inner end of the tufts of bristles in said openings.

13. An abrading brush comprising a rotatable member, a tuft of bristles, and means for rotatably mounting said tuft of bristles in the rotatable member on an axis radial to the rotatable member, whereby the rotation of the said rotatable member may cause a rotation of the tuft of bristles when the latter is engaged with a surface.
